UNITED STATES PATENT OFFICE.

JOHN H. KIEFFER, OF ALLENSTOWN, PENNSYLVANIA.

TOE-CALK.

1,099,605.

Specification of Letters Patent.

Patented June 9, 1914.

Application filed March 4, 1914. Serial No. 822,420.

To all whom it may concern:

Be it known that I, JOHN H. KIEFFER, a citizen of the United States, residing at Allentown, in the county of Lehigh and State of Pennsylvania, have invented a new and useful Toe-Calk, of which the following is a specification.

The present invention appertains to horseshoe calks, and more particularly to toe calks.

It is the object of the present invention to provide a toe calk for horseshoes, which shall be comparatively simple, non-encumbering and inexpensive in construction, which shall be of such construction, as to be readily applicable to and removable from the toe of a horseshoe, which shall be capable of withstanding the hard usage and strains to which it is subjected when in use, and which will otherwise be of advantage in its use.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein:—

Figure 1 is a bottom view of a horseshoe having the improved toe calk applied thereto. Fig. 2 is a sectional view taken on the line 2—2 of Fig. 1. Figs. 3 and 4 are sectional views taken on the lines 3—3 and 4—4, respectively, of Fig. 2.

In the drawing, the numeral 1 designates an ordinary horseshoe, and the numeral 2, designates generally, the improved toe calk.

The toe calk is constructed of hardened steel, or other suitable material, capable of withstanding wear and tear to a high degree. The toe calk 2 is disposed transversely across the bottom of the horseshoe, at the toe thereof, and the calk 2 is divided intermediate its ends by a diagonal cut 3, to provide two end sections 4 and 5, respectively. The adjacent or meeting ends of the calk sections 4 and 5 are beveled or cut obliquely, so as to overlap or fit snugly together, when the calk sections are alined,

the remote or outer ends of the calk sections being rounded or cut so as to conform to the outer edges of the horseshoe. The forward side of the calk is flat, and perpendicular to the horseshoe, while the rear side or face of the calk is preferably inclined or beveled, from the free or lower edge of the calk, to provide a sharp anti-slipping edge.

To attach the calk sections 4 and 5 to the horseshoe, the toe portion of the horseshoe is provided with laterally arranged or spaced threaded bores 6, which are provided at their lower ends with enlarged counterbores or sockets 7. Each of the calk sections is provided at its upper edge or basal portion, and intermediate its ends, with a boss 8 adapted to fit snugly within one of the counterbores 7, the boss 8 being provided with a threaded projection 9 engageable in the corresponding bore 6 of the horseshoe. Ordinarily, when the calk is in place, the bosses or studs 8 snugly engage the counterbores 7, while the threaded projections or stems 9 threadedly engage the bores 6, to maintain the calk sections firmly in position.

In order to clamp or secure the calk sections together, the adjacent ends of the calk sections are provided upon their rear side with a boss 10, which is disposed adjacent the horseshoe 1, and which is divided by the cut 3, the inner end of the calk section 5 carrying the greater portion of the divided boss 10. The adjacent ends of the calk sections are also provided with a bore or opening 11 adjacent the horseshoe, or the basal portions of the calk sections, the bore 11 being coaxial with the boss 10. The forward end of the bore 11 extends through the inner end of the calk section 4, while the rear end of the bore extends through the main portion of the boss 10 forming a portion of the inner end of the calk section 5. It may thus be said that the bore or opening 11 passes through the overlapping or meeting end portions of the calk sections.

To clamp the adjacent ends of the calk sections firmly together, a bolt 12 is passed through the bore or opening 11, the bolt being provided with an elongated head 13 at its forward end engaging the forward side of the calk section 4, and overlapping the forward side of the calk section 5, the bolt head 13 resting snugly against the bottom of the horseshoe. A clamping or retaining nut 14 is threaded upon the rear end of the bolt 12, and a nut-locking washer 15 is sand-

wiched or disposed between the nut 14 and the boss 10, the split washer and nut 14 seating against the boss 10 of the calk section 5, and slightly overlapping the rear face or side of that portion of the boss 10 carried by the inner end of the calk section 4. Thus, when the nut 14 is tightened, the adjacent ends of the calk sections will be tightly clamped together, in order that the 10 calk sections will present a substantial unitary calk construction.

In applying the toe calk to a horseshoe, after the threaded bores and counterbores 6 and 7, respectively, have been applied in 15 the toe portion of the horseshoe, one of the calk sections 4 is threaded in engagement with the corresponding bore 6, and when the said calk section has been completely engaged to the horseshoe, the same is reversed 20 for a quarter of a turn, so as to assume a longitudinal position. The other calk section is then threaded in engagement with the corresponding bore 6 of the horseshoe. Then, when the last mentioned calk section 25 approaches its normal or final position, both of the calk sections are turned so that the inner ends of the calk sections overlap or abut, when the calk sections are brought into alignment. It is to be noted that the 30 screw threads of the bores 6 and threaded stems or shanks 9 are all in the same direction, whereby the calk sections will rotate in the same direction when being threaded into engagement with the horseshoe, and in order 35 that the inner or beveled ends of the calk sections will swing together or meet properly. After the calk sections have thus been applied, the clamping bolt 12 is engaged through the bore 11. After the bolt 40 has been inserted through the bore 11, the washer 15 and nut 14 are applied to the bolt, and when the nut is tightened, the calk sections will be firmly clamped together. The toe calk thus presents a substantial anti- 45 slipping device for the shoe.

The bosses 8 engaging the counterbores 7, are of advantage, inasmuch as it is possible, in practice, that the screw threads will not permit the calk sections to aline at the same 50 moment that the calk sections seat against the horseshoe, which would necessitate a slight unscrewing of the calk sections, which would be objectionable. With the provision of the bosses 8 and counterbores 7, however, 55 the bosses 8 in engaging within the counterbores will take up the strains in an effective manner, notwithstanding the fact that the calk sections are slightly unscrewed when in normal position. Furthermore, the bosses 60 in fitting snugly within the counterbores 7 of the horseshoe, will also relieve the screw threads of considerable strain, as when the

calk is subjected to strains approximately parallel with the horseshoe.

The present calk may be readily applied to 65 and removed from the horseshoe, as is obvious from the foregoing, and is of advantage in other obvious respects, it being noted that the objects aimed at have been carried out satisfactorily. If desired, the toe calk 70 may be provided with a blunt edge, instead of a sharp one.

Having thus described the invention, what is claimed as new is:—

1. A toe calk having a diagonal cut intermediate its ends dividing it into two sections, the calk sections having threaded projections at their basal portions and intermediate their ends, the meeting ends of the calk sections having a bore therethrough, 80 one end of the bore extending through the corresponding end of one calk section, and the other end of the bore extending through the corresponding end of the other calk section, a bolt extending through the said bore 85 and having a head at one end seating against one side of one calk section and overlapping the corresponding side of the other calk section, and a nut engaged to the other end of the bolt and seating against the other side of 90 one calk section and overlapping the corresponding side of the other calk section.

2. A toe calk having its rear side inclined from the free edge of the calk, the rear side of the calk having a boss at the basal portion of the calk, the calk and its boss, being divided on a diagonal line, intermediate its ends, to provide two alining sections, the calk sections having threaded projections at their basal portions and intermediate their 100 ends, the adjacent ends of the calk sections having a bore therethrough coaxial with the said boss, the bore being disposed adjacent the basal portions of the calk sections, one end of the bore extending through the corresponding end of one calk section, and the other end of the bore extending through the corresponding end of the other calk section, a bolt fitting through the said bore and having an elongated head at its forward end 110 seating against the forward side of one calk section and overlapping the forward side of the other calk section, and a nut threaded upon the rear end of the bolt and seating against the boss sections of the two calk sections. 115

In testimony that I claim the foregoing as my own, I have hereto affixed my signature in the presence of two witnesses.

JOHN H. KIEFFER.
